UNITED STATES PATENT OFFICE.

URIAH McCLINCHIE, OF NEW YORK, N. Y., ASSIGNOR TO THE ELIZABETH OIL CLOTH COMPANY, OF ELIZABETH, NEW JERSEY.

DESIGN FOR ENAMELED CLOTH.

SPECIFICATION forming part of Design No. 16,096, dated May 19, 1885.

Application filed December 26, 1884. Term of patent 14 years.

To all whom it may concern:

Be it known that I, URIA McCLINCHIE, of the city, county, and State of New York, have invented a new and original Design for Enameled Cloth, of which the following is a full, clear, and exact description, reference being had to the accompanying drawing, making part of this specification, and which fully illustrates my invention.

10 The design relates to enameled cloth intended to represent woven-cane work.

Referring to the drawing, A represents the body of enameled cloth, and B B a series of main lines which intersect each other in

15 such a manner that star-shaped figures are formed by the same. The main lines B B are made of considerable width. Through the points of the star-shaped figures are drawn thinner lines C C, which intersect at the center of the star-shaped figures and in the center of the triangular points of the same. The

blending of the wider and thinner lines forms a star-shaped design in imitation of woven cane.

Having thus described my design, I claim as 25 new and desire to secure by Letters Patent—

The design for enameled cloth in imitation of woven cane, consisting of a series of intersecting star-shaped figures composed of a system of heavy intersecting diagonal and longitudinal lines, and a second system of finer diagonal and transverse lines intersecting at the centers of said heavy-lined stars, and also in the triangular arms thereof, substantially as shown.

30 In testimony that I claim the foregoing as my invention I have signed it this 18th day of December, 1884.

URIAH McCLINCHIE.
